MOTOR-DRIVEN TOOL

Henry E. Meltzer, Racine, Wis.

Application August 4, 1941, Serial No. 405,455

4 Claims. (Cl. 279—52)

This invention pertains generally to electrical-
ly driven tools, and more particularly to portable
hand tools.

In conventional tools of the foregoing type
provided with a tool chuck mounted upon the
armature shaft of the motor, difficulty has been
encountered in clamping the chuck because of
the free rotation of the motor shaft.

To overcome the foregoing objection, several
forms of locking devices have been devised to
lock the armature shaft against rotation while
manipulating the chuck.

However, as far as is known, such locking de-
vices comprise compressible plungers actuated
transversely of the armature shaft, thus tending
to spring the shaft, particularly when consider-
able force is exerted upon the chuck with a
wrench, plier or other tool in releasing or clamp-
ing the chuck.

The present invention has primarily for its
object to overcome the foregoing objections by
the provision of novel means for locking the
armature shaft of a motor driven tool against
rotation during manipulation of the chuck, and
which avoids any lateral strain upon the shaft.

Incidental to the foregoing, a more specific
object of the invention resides in the provision
of a compressible locking mechanism carried by
the chuck and longitudinally moveable with re-
lation to the armature shaft for locking the shaft
and chuck against rotation.

With the above and other objects in view,
which will appear as the description proceeds, the
invention resides in the novel construction, com-
bination and arrangement of parts, substantially
as hereinafter described, and more particularly
defined by the appended claims, it being under-
stood that such changes in the precise embodi-
ment of the herein disclosed invention may be
made as come within the scope of the claims.

In the accompanying drawing is illustrated one
complete example of the physical embodiment of
the present invention constructed according to
the best mode so far devised for the practical ap-
plication of the principles thereof.

In the drawing:

Figure 1 is a fragmentary elevation of an elec-
tric hand tool incorporating the present invention,
parts being broken away in sections to more
clearly illustrate structural details.

Figure 2 is a similar view.

Figure 3 is a detail elevational view of the
chuck and locking mechanism;

Figure 4 is the transverse sectional view taken
down the line 4—4 of Figure 3;

Figure 5 is similar view taken on the line 5—5
of Figure 1; and

Figure 6 is a transverse sectional view taken
out of the line 6—6 of Figure 1.

Referring now more particularly to the accom-
panying drawing, the numeral 1 designates a
casing consisting of an inner metallic sleeve 2,
surrounded by an outer plastic shell 3.

Housed within the casing is a conventional
electric motor 4 having an armature shaft 5,
which is journaled at its forward end in a bearing
6, carried by a head 7 secured within the
end of the metallic sleeve 2.

The outer end of the head 7 is provided with
a recessed boss 8 for reception of the shank 9
of the tool chuck, the outer end of the shank being
slotted, and exteriorally threaded to receive a
tapered cap 10, which serves to clamp the shank
of a tool 11 within the chuck.

The shank 9 of the chuck is secured to the
armature shaft 5 by a set screw 12, as best shown
in Figure 6, while the rear end of the shank is
journaled within a recess 13 formed in the head
7. The boss 8 is provided with a tool opening 8'
25 to facilitate the adjustment of the set screw 12.

Adjacent its inner end the chuck shank 9 is
provided with a flange 14 located within the re-
cessed boss 8 and provided with a plurality of
30 radially spaced openings 15 for alignment with
pockets 16 formed in the head 6.

Slidably mounted upon the other end of the
shank 9 is a disc 17, to which a plurality of pins
18 are secured, the ends of the pins extending
35 into the openings 15 in the chuck flange 14, as
best shown in Figure 1. A coil spring 19 is dis-
posed between the flange 14 and the disc 17 and
the spring functions to normally hold the disc
17 against the chuck cap 10.

In its normal position the disc 17 is flush with
40 the outer end of the recessed boss 8, as shown in
Figures 1 and 2, and in order to facilitate de-
pression of the disc the recessed boss 8 is pro-
vided with oppositely disposed cut out portions 20.

In operation, when it is desired to manipulate
the chuck cap 10 for removal or insertion of
the tool 11, the operator merely depresses the
disc 17 with his finger to project the pins 18 into
50 the pockets 16 formed in the head 6, thus lock-
ing the chuck shank 9 and the armature shaft
5 against rotation as the chuck cap 10 is turned
on the shank 9.

To facilitate locking of the chuck and arma-
ture shaft the recessed boss 8 is provided with an
indicia 17', which enables the operator to properly

align the pins 18 for projection into the pockets 16.

From the foregoing explanation considered in connection with the accompanying drawing, it will be seen that an exceedingly simple and compact mechanism has been provided for locking the armature shaft of a motor driven tool against rotation during manipulation of the tool chuck, and at the same time there are no lateral projections such as plungers to interfere with manipulation of the tool, or allow unintentional locking of the shaft while the motor is in operation.

It will also be appreciated that the present invention serves to lock the chuck shank, and consequently motor shaft at a plurality of radially spaced points, thus securely holding the shaft against lateral springing in the event of undue force being exerted upon the chuck cap by means of wrenches or other tools.

I claim:

1. In a motor driven tool including a casing, a head secured to one end of the casing, a rotatable shank having a tool chuck extending beyond said head, a manually depressible disc non-rotatably mounted on said chuck and longitudinally movable thereon said head having keeper openings therein, and annularly spaced pins carried by said disc for engagement in the keeper openings in said head, when the sleeve is in one of its positions for locking said chuck and casing head against relative rotary movement.

2. In a motor driven tool including a casing, a head secured to one end of the casing, a rotatable shank having a tool chuck extending beyond said head, said chuck including a locking cap, a manually depressible disc non-rotatably mounted on said chuck and longitudinally movable thereon, said head having keeper openings therein, annularly spaced pins carried by said disc for engagement in the keeper openings in said head when the sleeve is in one of its positions for lock-

ing said chuck and casing head against relative rotary movement, and spring means normally holding the disc against said cap and the pins out of locking engagement with the head.

5 3. In a motor driven tool including a casing, a head secured to one end of the casing provided with an outwardly extending hollow boss, a rotatable shank having a tool chuck rotatable in said hollow boss and with the forward end thereof 10 extending beyond said hollow boss, a manually depressible disc non-rotatably mounted on said chuck and disposed within said hollow boss for movement longitudinally of the chuck and boss, said head having keeper openings therein, and annularly spaced pins carried by said disc for engagement in said keeper openings in said head when the disc is in one of its positions for locking said chuck and casing head against relative rotary movement, said boss being partially cut 15 away at its forward end, whereby to permit the engagement of the fingers of the operator with said disc.

10 4. In a motor driven tool including a casing, a stationary head carried by one end of the casing provided with an annular row of spaced openings, a rotatable shank extending through said head having a tool chuck extending beyond said head, an outwardly extending flange formed on the inner end of the chuck for rotation therewith provided with openings therethrough for alignment with the openings in the head, a manually depressible disc slidably mounted on said chuck, annularly spaced pins carried by said disc slidably mounted in the openings in the flange and movable into the openings in the head when said disc is moved toward the flange, and a spring coiled about said chuck and disposed between the flange and disc for normally holding the disc away from the flange and the pins out of the openings in the head.

HENRY E. MELTZER.
